UNITED STATES PATENT OFFICE

2,354,680

RAILWAY CAR END WALL

Garth G. Gilpin, Riverside, Ill., assignor to Standard Railway Equipment Manufacturing Company, Chicago, Ill., a corporation of Delaware

Application May 30, 1942, Serial No. 445,130

14 Claims. (Cl. 105—410)

The invention relates to railway cars and parts thereof and more particularly to the end walls of railway freight cars.

Such end walls for railway cars are required to resist the terrific forces of shifting lading, such as piping, steel plates and planed lumber caused by the service movements of the car, particularly switching, coupling and air brake applications. To resist such forces end walls have been made of one-quarter inch steel plates reinforced by a plurality of integral contiguous parallel corrugations which are generally horizontally disposed so that the several corrugations function as a series of cooperating beams to transfer such force to the corner posts (or other frame members) of the car.

In this specification I describe my reinforced metallic plate as providing an end wall for a railway car, but it may also be used as a side door for a railway house car; a drop door for a railway general service gondola car; a hopper door for a railway hopper car or a roof for a railway house car.

The safety appliance rules of the Interstate Commerce Act require a clearance of at least 12" from the outer surfaces of the end ladder rungs to a vertical plane passing through the pulling face of the coupler knuckle when the striking head of the coupler is against the buffer on the car. This is called the "end ladder clearance" and cars not so arranged are subject to a One Hundred Dollar (\$100.00) fine and may only be moved by a railroad to the nearest repair shop.

In actual practice railway cars equipped with corrugated metallic end walls are arranged to provide a little more than the legally required "end ladder clearance" so that if the corrugated plate bulges a little the car will still have the necessary "end ladder clearance."

One of the objects of the invention is to form a relatively thin metallic plate with a plurality of parallel corrugations with the metal so disposed as to provide a series of beams of great strength compared to the weight of the metal used and to apply such relatively thin metallic plate so corrugated to a railway car to constitute an end wall therefor wherein an end ladder may be attached thereto so as to provide the legally required "end ladder clearance," and at the same time, provide a railway car of greater inside length and lesser train length than has heretofore been designed.

This invention is an improvement over the corrugated end walls disclosed in Small's Patents No. 1,681,811 and No. 1,681,816, both of August 21,

1928, hereinafter referred to as Small's corrugated end wall, and the construction shown in my own Patent No. 2,223,609 of December 3, 1940.

In the drawings:

Figs. 1—4, inclusive, show a typical form of my invention applied to a railway car wherein—

Fig. 2 is a section on line 2—2 of Fig. 1.

Fig. 3 is a section on line 3—3 of Fig. 1.

Fig. 4 is a section on line 4—4 of Fig. 1.

Figs. 5—8, inclusive, show a single plate formed similarly to the plate shown in Fig. 1 wherein—

Fig. 6 is a section on line 6—6 of Fig. 5.

Fig. 7 is a section on line 7—7 of Fig. 5.

Fig. 8 is a section on line 8—8 of Fig. 5.

Figs. 9 to 12, inclusive, show a single plate formed according to a modification of my invention with the ladder rungs mounted thereon ready for mounting upon a car to form part of the end wall thereof wherein—

Fig. 10 is a section on line 10—10 of Fig. 9.

Fig. 11 is a section on line 11—11 of Fig. 9.

Fig. 12 is a section on line 12—12 of Fig. 9.

Figs. 13—16, inclusive, are similar to Figs. 5—8 inclusive and show another modified construction wherein—

Fig. 14 is a section on line 14—14 of Fig. 13.

Fig. 15 is a section on line 15—15 of Fig. 13.

Fig. 16 is a section on line 16—16 of Fig. 13.

Fig. 17 is a bending moment and section modulus diagram of a corrugation and reinforcing rib of my corrugated plate as an equally loaded beam.

Fig. 18 is a plan view showing the end portions of two diagrammatically indicated cars coupled together to illustrate the "end ladder clearance."

Railway house and gondola cars are now in use having end walls comprising quarter inch metallic plates formed with a plurality of horizontally disposed corrugations as disclosed in Small Patents No. 1,681,811 and No. 1,681,816

heretofore mentioned but owing to the increased tempo of freight car movement with the resultant high speed of freight trains; heavier loading of freight cars; the coupling and switching at higher speeds, etc., all of which increase the force imposed upon the end wall of the car, either by a shifting load or a tendency of the load to shift, it may be desirable to materially increase the strength of the corrugated end wall plate.

The Small end walls disclosed in his patents mentioned above could be strengthened by increasing the thickness of the metallic plate from one-quarter inch to say three-eighths inch, but this would increase the weight of the end wall fifty percent, requiring the movement of that

much more weight around the country, as well as increase the cost of material and cost of pressing the thicker plate.

The above Small corrugated end walls, as disclosed in the enumerated patents, could theoretically be strengthened by enlarging the corrugations. This, however, is a theory but not a fact. The present marketed design of Small end is made of one-quarter inch plate with three inch deep corrugations on twelve inch centers at the middle of the wall; that is, midway between the corner posts. If these dimensions were increased to four inches and fifteen inches, respectively, the section modulus of each corrugation, as well as the section modulus of the corrugated plate, would theoretically be naturally increased, but the fact is that the metallic compression apices of the corrugations, that is, the metal in the extreme compression and sides of the corrugations, is not strong enough to transfer the stresses imposed thereon to the adjacent walls of the corrugations and, therefore, these compression sides will buckle causing a failure of the corrugations. (See Gilpin Patent No. 2,223,609 of December 3, 1940.)

In my improved corrugated end wall I have enlarged the central portions of the corrugations of the small corrugated end wall by increasing the depth **4** of the corrugations **2** from three inches to four inches and increasing the distance **3** between the centers of the corrugations **2** from twelve inches to fifteen inches. I overcome the weakness in the compression sides **4** mentioned above by forming a reinforcing small rib **5** (or corrugation **5**) in the compression sides **4** of the corrugated wall which increases the strength thereof to resist buckling and enables them to transfer the forces imposed thereon to the adjacent walls **6** of the corrugations. (This feature per se is disclosed and claimed in my Patent No. 2,223,609.)

If the end portions **8** of the above mentioned enlarged corrugations **2** were made deep enough to develop strength of the enlarged middle portions thereof (when considered as beams with equally distributed loads thereon) such end portions would be so deep that if the end ladder rungs **11** were mounted thereon the "end ladder clearance" **56** between adjacent cars would be reduced or if the legally required "end-ladder clearance" is provided the train length **58** of the car would be increased or the inside length **59** of the car decreased. (See Fig. 18.)

The end portions **8** of the major corrugations **2** are made deep enough to project between the ladder rungs **11**, but not beyond the outer surface of the ladder rungs. When the end portions **8** of the major corrugations **2** are about three inches deep and the end portions **12** of the reinforcing ribs **5** are one and one-half inches deep, the combined section modulus thereof is sufficient to develop the strength of the central portion of the four inch deep corrugation.

The safety appliance rules referred to above require a clear space of two and one-half inches around the tread of each ladder rung. If the end portions **8** of the major corrugations **2** were extended to the plane **14** of the outside of the ladder rungs **11** they would interfere with the toe of a man using the ladder, therefore, it is desirable to provide clear space **15** between the treads of the ladder rungs, which I accomplish by not extending the end portions **8** of the major corrugations **2** beyond a plane **16** parallel to but within the vertical plane of the outside of the treads of the ladder rungs **11**.

The combined strength of the end portions **8** of the major corrugations **2** and end portions **12** of the reinforcing ribs **5** is sufficient to develop the combined strength of the main corrugations **2** and reinforcing ribs **5** at the middle thereof when the plurality of main corrugations and reinforcing ribs are considered as beams supporting an equally distributed load between the corner posts of the car. When figuring the strength of the corrugated end wall as shown in Figs. 1-4, inclusive, each pair of major corrugation **2** and reinforcing rib **5** is figured as a beam between its points of support which are the corner posts of the car. Fig. 17 shows the bending moment parabola **17** and the section moduli line **18** between the points of support **19-19**. The section modulus line **18** is always above the bending moment parabola **17** which shows that the beam is strong enough at all places to support the load.

I preferably also proportion the major corrugations **2** and reinforcing ribs **5** so that the length of the center line of the metal of a cross section of the combined major corrugations and reinforcing ribs is substantially the same as any other cross section, thus making the plate easy to form on reciprocating dies by equalizing the stretch and draw-in of the metal during the forming operation.

By increasing the depth and spacing of the corrugations and providing the reinforcing ribs in the compression sides of the several corrugations and by gradually increasing the depth (and preferably also the width) of the reinforcing ribs **5** toward their opposite ends and securing the ladder rungs **11** to the end portions **12** of these reinforcing ribs, I obtain an end wall actually thirty-six percent stronger with the same thickness of metallic plate with only a four percent increase in weight. This increase in weight is due to the fact that in forming the deeper corrugation more material is "drawn in" by the action of the reciprocating dies.

Figs. 5, 6, 7 and 8, inclusive, show a single plate similar to the plate shown on the end wall of Fig. 1 but with the end portions **20** of the major corrugations **21** shallower than the end portions **22** of the reinforcing ribs **23** and the ladder rungs **24** mounted upon the relatively shallow end portions **20** of the major corrugations **21**.

In Figs. 5 and 7 I have shown the treads of the ladder rungs above the attaching rivets which may be advantageous in some cases.

Figs. 9 to 12, inclusive, show a single plate according to a modification of my invention wherein a relatively thin metallic plate is formed with a plurality of corrugations **30-31** with their opposite ends **32** terminating into the plate which would be adjacent corner posts of the car, as shown in Figs. 1 and 2. Some of the corrugations (preferably in pairs) merge together between their ends to form a lesser number of wider corrugations **33**, and preferably deeper corrugations substantially midway between the ends of the corrugations which, when applied to the car, would be substantially midway between the corner posts of the car. Some of the first mentioned corrugations (shown as **30**) are formed with shallow end portions upon which the ladder rungs **34** are mounted so as to increase the end ladder clearance when the plate is installed upon a car.

Figs. 13 to 16, inclusive, show a single plate according to another modification of my invention wherein a relatively thin metallic plate is formed with a plurality of major corrugations **40** with their opposite ends terminating into the

plate which would be adjacent the corner posts of the car, as shown in Figs. 1 and 2. The plate is also formed with pairs of aligned shallower minor corrugations 41—42 positioned between adjacent major corrugations 40 with their inner ends 43 terminating into the plate and with their outer ends 44 terminating into the plate substantially in line with the outer ends of the major corrugations. The ladder rungs 45 are mounted upon the shallower minor corrugations to increase the end ladder clearance.

Any of the described types of corrugated plates having a shallow corrugation, or a corrugation having a shallow portion to accommodate a ladder rung may be used as part of a side door for a railway car wherein such shallow corrugation or shallow part of a corrugation may be used to accommodate a side door lock, hasp, closing mechanism, hinge, etc., wherein it is desirable to set such devices back of the outer plane of the side door to keep the door within the established overall width of the car (Association of American Railroads 10'8") and at the same time increase the width of the lading space within the car.

Fig. 18 is a diagram showing the end portions of two coupled cars to illustrate the Interstate Commerce Commission requirements for "end ladder clearance" under its safety appliance rules wherein the line 50 represents a vertical plane passing through the pulling faces 51 of the coupler knuckles 52 when the striking heads 53 are against the buffers 54 on the cars and the ladder rung 55 represents the end ladder and the space 56 shows the "end ladder clearance" which according to law must be at least twelve inches. From this diagram it will be seen that if the dimension 56 remains constant and the depth 57 of the corrugation is decreased the train length 58 is decreased, or if the train length is not decreased, the inside length of the lading space 59 may be increased.

The above mentioned safety appliance rules require that the ladder treads of the end ladder be spaced vertically not more than nineteen inches apart, therefore, I preferably arrange and position the corrugations accordingly so as to eliminate the necessity of providing ladder stiles. The fifteen inch centers of major corrugations heretofore mentioned meet these requirements.

The accompanying drawings illustrate the preferred form of the invention, though it is to be understood that the invention is not limited to the exact details of construction shown and described, as it is obvious that various modifications thereof, within the scope of the claims, will occur to persons skilled in the art.

I claim:

1. A railway car wall comprising a metallic plate adapted to extend between and be secured to spaced apart frame members of the car, said plate formed with a plurality of horizontally disposed sinuous corrugations providing a plurality of cooperating beams extendable between said frame members, every other of said corrugations being formed with end portions shallower than the end portions of the corrugations therebetween and ladder rungs mounted upon said shallower end portions parallel therewith and which project beyond the corrugations therebetween.

2. A railway car wall comprising a metallic plate adapted to extend between and be secured to spaced apart frame members of the car, said plate formed with a plurality of horizontally disposed sinuous corrugations providing a plurality

of cooperating beams extendable between said frame members, some of said corrugations being formed with end portions shallower than the end portions of the other of said corrugations and ladder rungs mounted upon said shallower end portions parallel therewith and which project beyond the other of said corrugations.

3. A wall for a railway car comprising a metallic plate adapted to be secured to oppositely disposed frame members of the car and provided with a plurality of horizontally disposed major corrugations extendable substantially between the frame members and terminating into the plate adjacent said frame members and a pair of aligned shallower horizontally disposed minor corrugations positioned between adjacent major corrugations with their inner ends terminating into the plate and with their outer ends terminating into the plate in line with the outer ends of the major corrugations and ladder rungs mounted upon some of said shallower minor corrugations parallel therewith and which project outwardly beyond the major corrugations.

4. A railway car wall comprising a metallic plate adapted to extend between and be secured to spaced apart frame members of the car, said plate formed with a plurality of horizontally disposed corrugations extendable between and with their opposite ends terminating into the plate adjacent said frame members, some of said corrugations merging together between their ends to form a lesser number of wider corrugations, some of said first mentioned corrugations being formed with shallow end portions and ladder rungs mounted upon said shallow end portions parallel therewith and which project outwardly beyond the other of said first mentioned corrugations.

5. A railway car wall comprising a metallic plate adapted to extend between and be secured to spaced apart frame members of the car, said plate formed with a plurality of horizontally disposed deep corrugations alternating with corrugations which are shallower than the deep corrugations for the entire length thereof so as to provide a plurality of cooperating beams extendable between said frame members and ladder rungs mounted upon the end portions of said shallower corrugations parallel therewith and which project beyond the deep corrugations.

6. A railway car wall comprising a metallic plate adapted to extend between and be secured to spaced apart frame members of the car, said plate formed with a plurality of horizontally disposed deep corrugations which decrease in width toward their opposite ends alternating with shallower corrugations which increase in width toward their opposite ends thus providing a plurality of cooperating beams extendable between said frame members, the end portions of the shallower corrugations being of less depth than the end portions of the deep corrugations, and ladder rungs mounted upon the end portions of the shallower corrugations parallel therewith and which project beyond the deep corrugations.

7. A wall for a railway car comprising a metallic sheet of substantially uniform thickness at any transverse cross section thereof adapted to extend between and be secured to spaced apart frame members of the car and formed with a plurality of horizontally disposed sinuous alternating major and minor corrugations extendable substantially between said frame members and merging into said sheet adjacent said frame members, said major corrugations being deep and

wide at the middles thereof and decreasing in depth and width toward the opposite ends thereof, said minor corrugations being shallower than the major corrugations for the entire lengths thereof and increasing in depth and width toward the opposite ends thereof, whereby the major and minor corrugations are cooperatively associated and relatively proportioned to develop the maximum strength of the corrugations as beams at any cross section thereof to carry stresses imposed thereon to said frame members.

8. A structure as defined in claim 7 including ladder rungs mounted upon the end portions of the minor corrugations and parallel therewith, with the ladder rungs projecting outwardly beyond the major corrugations.

9. A structure as defined in claim 7 wherein the end portions of the minor corrugations are of constant depth for a short distance, and ladder rungs are mounted upon said constant depth portions and project outwardly beyond the major corrugations.

10. A metallic plate of substantially uniform thickness at any transverse cross section thereof formed with a plurality of parallel sinuous alternating major and minor corrugations extending from substantially one edge of said plate to the opposite edge thereof, said major corrugations being deep and wide at the middles thereof and decreasing in depth and width toward the opposite ends thereof, said minor corrugations being shallower than the major corrugations for the entire lengths thereof and increasing in depth and width toward the opposite ends thereof, said major and minor corrugations being so proportioned and cooperatively arranged that the section modulus curve substantially follows the bending moment curve, thereby providing a plate having maximum resiliency and strength for an equally distributed load.

11. A metallic plate of substantially uniform thickness at any transverse cross section thereof formed with a plurality of parallel sinuous alternating major and minor corrugations extending from substantially one edge of said plate to the opposite edge thereof, said major corrugations being deep and wide at the middles thereof and decreasing in depth and width toward the opposite ends thereof, said minor corrugations being

shallower than the major corrugations for the entire lengths thereof and increasing in depth and width toward the opposite ends thereof, the combined strength of the end portions of the major corrugations and end portions of the minor corrugations being sufficient to develop the combined strength of the major corrugations and minor corrugations at the middles thereof when the plurality of major corrugations and minor corrugations are considered as beams supporting an equally distributed load.

12. A metallic plate of substantially uniform thickness at any transverse cross section thereof adapted for use in a railway car having spaced frame members, said plate formed with a plurality of parallel sinuous alternating major and minor corrugations adapted to extend between and to said frame members, said major corrugations being deep and wide at the middles thereof and decreasing in depth and width toward the opposite ends thereof, said minor corrugations being shallower than the major corrugations for the entire lengths thereof and increasing in depth and width toward the opposite ends thereof, said major and minor corrugations being so proportioned and cooperatively arranged when acting as beams supporting an equally distributed load between said frame members that the section modulus curve substantially follows the bending moment curve thereby providing a plate having maximum resiliency and strength for an equally distributed load.

13. A metallic plate of substantially uniform thickness at any transverse cross section thereof formed with a plurality of like pairs of corrugations, the corrugations of each pair being dissimilar and each extending from substantially one edge of said plate to substantially the opposite edge thereof, said pairs of corrugations being so proportioned and cooperatively arranged that the section modulus curve substantially follows the bending moment curve, thereby providing a plate having maximum resiliency and strength for an equally distributed load.

14. A metallic plate formed as defined in claim 10 wherein the end portions of the minor corrugations are of constant depth for application of grab irons thereto.

GARTH G. GILPIN.
